UNITED STATES PATENT OFFICE

GEORGE B. PICKOP, OF NEW HAVEN, CONNECTICUT, ASSIGNOR TO MALLEABLE IRON FITTINGS COMPANY, OF BRANFORD, CONNECTICUT

VIBRATOR

Application filed October 16, 1931. Serial No. 569,289.

This invention relates to vibrators and more particularly to a fluid-operated vibrator provided with a hollow casing or cylinder and a reciprocating piston operating therewithin. Vibrators of this type are commonly operated by compressed air, and it is, of course, necessary to insure that the operating fluid passes first to one end and then to the other end of the cylinder in order that the piston be kept in operation. This is usually accomplished by providing air passages in the wall of the casing and so forming the piston that the parts of the piston, itself, will serve to cut off or permit communication between the source of compressed air and the ends of the cylinder, so that no valve and valve gear is required to effect continuous reciprocation of the piston.

In the past, it has been considered necessary to provide a number of passages, usually four, there being two at each end, in the vibrator casing, and to connect these passages with the interior of the casing or cylinder by transverse ports or passages. Usually six of these latter ports are required. I have found, however, that by making certain more or less simple changes in the piston, I am enabled to omit a number of the longitudinal and transverse passages in the vibrator body and thus substantially reduce the cost of manufacture of the vibrator, and at the same time produce an efficiently operating device which will operate positively and effectively.

One object of my invention is the provision of a vibrator which will be efficient in operation and at the same time be economical to manufacture.

A further object of the invention is the provision of a vibrator comprising a casing and a piston reciprocating therein, in which the operating fluid will be conducted from the central portion of the casing to the end portions by passages formed in the piston, thus reducing the number of passages required to be formed in the vibrator casing.

Still another object of the invention is the provision of an improved fluid-operated vibrator which may be manufactured more

economically than those in use at the present time.

To these and other ends, the invention consists in the novel features and combinations of parts to be hereinafter described and claimed.

In the accompanying drawing:

Fig. 1 is a top plan view of a vibrator embodying my invention;

Fig. 2 is a sectional view on line 2—2 of Fig. 1;

Fig. 3 is a sectional view on line 3—3 of Fig. 2;

Fig. 4 is a top plan view of the reciprocating piston, and

Fig. 5 is a side elevational view of the same.

The vibrator which I have chosen to illustrate and describe as a preferred embodiment of my invention comprises a casing 10, bored out to provide a cylinder 11, the ends of which are closed by the heads 12 and 13 which, as shown, may be threadedly secured to the vibrator body or casing 10. Within the cylinder a reciprocating piston 14 is disposed, and, as will be more fully explained hereinafter, this piston is designed to be operated by a fluid under pressure such as compressed air so that it will be reciprocated in a back and forth movement and strike against the heads 12 and 13 to set up vibrations in the casing 10 and, through the attaching member 15 in any object 16 to which the vibrator may be secured.

It will be noted that, as shown in Fig. 2, the bore 11 is eccentric to the casing 10 so as to leave a considerable amount of metal at one side, in this instance the upper side of the casing. In this portion of the casing are provided the longitudinal air passages 17 and 18 which may be conveniently formed by being drilled from the ends of the casing, the openings being afterwards closed by the plugs 19 and 20. It will be noted that it is only necessary to drill one of these passages in each end of the casing.

Communicating bores or passages 21, 22, 23 and 24 are then formed transversely of the passages 17 and 18 to effect communication between these passages and the interior

100

or cylinder of the vibrator body. These bores may be conveniently formed by drilling through the top of the casing and closing the outer ends of the bores with plugs

5 25. The casing is also provided with a threaded opening 26 leading into the cylinder, within which opening may be secured a proper connection (not shown) leading to a suitable supply of fluid pressure such as

10 compressed air.

15 The piston 14, as shown in Figs. 4 and 5, is provided with reduced end portions 27 and 28, and a number of annular grooves, there being three of such grooves 29, 30 and 31 in the piston illustrated. The groove 30 is formed at substantially the central portion of the piston, the others 29 and 31 being disposed between this central groove and the end portions. A slot 32 serves to connect the groove 30 with the grooves 29 and 31, which slot may be conveniently formed by a milling operation. It will be apparent from this construction that any fluid pressure reaching the groove 30 will be communicated by the slot 32 to the end grooves 29 and 31. Exhaust ports 33 and 34 are formed in the casing adjacent the ends of the cylinder to permit the venting of the pressure fluid at the end of the stroke of

20 30 the piston.

Referring to Fig. 2 of the drawing, it will be observed that the grooves 29 and 31 are spaced apart a distance less than that between the ports 22 and 23, and that the 35 stroke of the piston is of such length that the groove 30 is always in communication with the opening 26 leading to the source of compressed air. The spring 35, as is well understood, is intended only to insure that

40 the piston will come to rest at one end of the casing, as in operation the piston will be driven in both directions by fluid pressure.

The operation of my device may now be 45 briefly described. With the parts in the position shown in Fig. 2, the piston being held at the right-hand end of the cylinder by the spring 35, a fluid under pressure, such as compressed air, is admitted through the opening 26. The compressed air so admitted enters the groove 30 and is carried by the slot 32 to the grooves 29 and 31 regardless of the position of this slot, for it will be understood that the piston in its 50 operation may rotate within the cylinder so that the slot 32 may not always lie directly below the opening 26. It will be observed that the groove 31 is in communication with the port 23, while the port 22 is closed by the solid part of the piston beyond the groove 29, the left-hand end of the cylinder being in communication with the exhaust port 33 at this time. The compressed air, therefore, may enter the port 23, but is prevented from entering the port 22. This air

flows through the passage 18 and the port 24 into the right-hand end of the cylinder so that it may act upon this end of the piston to drive it toward the left.

When the piston reaches the left-hand end 70 of the cylinder, the port 23 will have been closed by the solid portion of the piston, and the port 22 will be in communication with the groove 29, the right-hand end of the cylinder being exhausted through the port 34. The source of compressed air is at that time cut off from the right-hand end of the piston, but placed in communication with the left-hand end through the passage 75 17 and port 21 so that it will act against the left-hand end and drive the piston to the right.

It will, therefore, be apparent that a continuous reciprocating movement of the piston will be effected as long as the opening 26 85 is in communication with a source of compressed air, and that this air will be alternately admitted to and cut off from the ends of the cylinder, and that this is accomplished with a minimum number of passages 90 in the vibrator casing in conjunction with the slot 32 formed in the piston. As this slot may be formed by a milling operation a considerable economy is achieved in the manufacture of the device.

95 While I have shown and described a preferred embodiment of my invention, it will be understood that it is not to be limited to all of the details shown, but is capable of modification and variation within the spirit 100 of the invention and within the scope of the appended claims.

What I claim is:

1. A vibrator comprising a casing having a cylinder formed therein, a piston mounted to reciprocate in said casing, said casing being provided with a substantially centrally located opening extending through the wall thereof to communicate with the cylinder, said piston being provided with an intermediate annular groove substantially midway between its ends, and an outer annular groove between said first-named groove and each end of the piston, the surface of said piston being provided with a longitudinal groove extending from one of said outer annular grooves to the other and passing through said intermediate groove, and said casing wall being provided with passages leading from points adjacent the outer annular grooves of the piston to the ends of the cylinder.

2. A vibrator comprising a casing having a cylinder formed therein, a piston mounted to reciprocate in said casing, said casing being provided with a substantially centrally located opening extending through the wall thereof to communicate with the cylinder, said piston being provided with an intermediate annular groove substantially mid-

way between its ends, and an outer annular groove between said first-named groove and each end of the piston, the surface of said piston being provided with a longitudinal groove extending from one of said outer annular grooves to the other and passing through said intermediate groove, and said casing wall being provided with passages leading from points adjacent the outer annular grooves of the piston to the ends of the cylinder, said longitudinal groove comprising a milled slot in the surface of the piston, the ends of which terminate in the outer annular grooves.

In witness whereof, I have hereunto set my hand this 14th day of October, 1931.

GEORGE B. PICKOP.
